FATTY ACIDS FROM COTTONSEED FOOTS

Herbert K. McClain, Wyoming, Ohio, assignor to
The Procter & Gamble Company, Cincinnati,
Ohio, a corporation of Ohio

No Drawing. Application December 6, 1943,
Serial No. 513,172

8 Claims. (Cl. 260—419)

1

This invention relates to a process for producing fatty acids of improved quality from cottonseed oil refining foots.

In the refining of crude cottonseed oil by treatment with caustic soda a by-product is obtained which is commonly referred to as "cottonseed foots." It is an emulsified mixture of hydrated sodium soaps of the fatty acids of cottonseed oil and neutral triglyceride oil, together with coloring matter, mucilaginous materials, and other impurities removed from the crude cottonseed oil during the refining process. The soaps and the neutral oil have commercial value, and this is enhanced by freeing them, or their fatty acids, from the impurities with which they are associated in the foots.

The undesired impurities in cottonseed foots have been separated more or less completely, and useful products prepared from the soaps and glyceride oil of the foots in various ways. One of the oldest procedures is to boil the foots with caustic soda until the neutral oil is saponified, wash the soap several times with water or dilute caustic solutions, and finally "pitch" the soap as in making any fitted or "neat" kettle soap. Although this procedure has the advantage of simplicity, it is today of limited utility because the resulting soap is dark or yellowish in color, strong in odor, and poor in keeping quality when exposed to the air.

The procedure most commonly employed in recent years, which employs the so-called Twitchell process, consists in acidulating the foots to convert the soaps to free fatty acids, followed by boiling the oily mass with dilute sulfuric acid solution and an emulsifying agent (a "saponifier") to hydrolyze the glyceride oil and convert it into free fatty acids and glycerin. The mixture of fatty acids thus obtained is black in color, and is usually purified by distillation. The distilled cottonseed foots fatty acids are relatively light in color and are suitable for use in the manufacture of laundry soaps and intermediate grade general household soaps.

Another procedure that had its origin many years ago is a combination of parts of each of the two preceding methods. It consists in boiling the foots with caustic soda in a soap kettle, to saponify the neutral oil, washing several times with water or dilute caustic solutions to remove some of the coloring matter and impurities, graining out with salt after each of these kettle operations, then acidulating the finally settled soap with mineral acid to liberate the free fatty acids from the soaps, and finally purifying the

2

free fatty acids by distillation. This produces a somewhat better quality of fatty acids than the Twitchell method, but usually at the sacrifice of the glycerin, which is readily recoverable from the Twitchell saponification acid water but which is not so economically recoverable from the caustic saponification lye.

The present invention is an improvement on the procedure described in the preceding paragraph, although it is applicable not only to the original or "raw" foots from the oil refining process, but also to acidulated foots such as those normally subjected to Twitchell saponification. By means of this invention the quality of the resulting distilled fatty acids is strikingly improved. Furthermore, the kettle boiling process is simplified because the washing of the caustic saponified foots with water or dilute caustic is rendered unnecessary.

20 An object of the invention is to produce from cottonseed foots a quality of fatty acids superior to that resulting from prior methods, and suitable for use in lighter colored soaps.

Another object is to lessen the cost and shorten 25 the time required for the making of soaps from cottonseed foots.

Another object is to produce cottonseed foots fatty acids which are relatively stable in color, and which produce light colored soaps which retain a good color with relatively little reversion even under severe aging conditions, and which are relatively very free from disagreeable fatty acid odors.

Another object is to provide a process for 30 accomplishing the foregoing ends which is applicable to both raw cottonseed foots and acidulated cottonseed foots.

Another object is to fix or transform the coloring materials in cottonseed foots in such a manner that they do not distill over with the foots fatty acids.

Other objects are to accomplish these ends by means of an oxidizing agent which is effective under alkaline conditions, and by means of an 35 oxidizing agent having a cation which forms water soluble soaps.

In the practice of a preferred modification of the present invention, a quantity of the foots resulting from the caustic refining of crude cottonseed oil is pumped into a soap kettle in which there is a boiling solution containing a low concentration of sodium hydroxide and a somewhat higher concentration of ordinary salt. After saponification of the oil in the foots is well started, a small quantity of an oxidizing agent, of the

type which is effective in an alkaline medium and which has a cation which forms water soluble soaps of soap making fatty acids, is added and distributed throughout the boiling mass. As a preferred example of this class of oxidizing agent I may use potassium persulfate ($K_2S_2O_8$). The amount of this persulfate, which is conveniently added in dry powdered form, may be from about 0.05 per cent to about 0.5 per cent of the weight of raw foots charged into the kettle, 0.1 per cent being a suitable amount in many cases.

After the addition of the oxidizing agent, which has been found to cause the boiling mass to become darker in color, the boiling of the kettle is continued for several hours until the saponification of the foots is substantially complete—additional caustic soda (usually as a fairly strong solution) being added from time to time if required. The soap if not already in a grainy condition is then grained out by adding salt, the steam heat is shut off, and the kettle is allowed to settle for several hours. An aqueous layer, together with a small amount of finely divided insoluble impurities, settles out below an upper layer of soap.

The soap layer is then transferred to a wooden or to a lead-lined tub containing a boiling sulfuric acid solution. This solution may be of any convenient concentration, e. g. 50% sulfuric acid. The amount of the solution used is preferably such that when the acid has broken up substantially all the soaps and has liberated their fatty acids, a slight excess of sulfuric acid will remain. When this point has been reached the boiling is discontinued, the tub is allowed to stand until the aqueous acid layer has dropped from the fatty acids; this aqueous seat is withdrawn; hot water containing a small amount of sulfuric acid is added and boiled with the fatty acids to complete the acidulation of the soaps and to wash out sodium sulfate; the tub is again settled, and this second seat is withdrawn. This washing and settling procedure is repeated at least once more, this time with water alone and no acid. The trace of mineral acid which may then be present in the fatty acids is neutralized, for example by adding a small amount of barium carbonate. The fatty acids are then transferred to a vacuum still, and distilled according to well known practice.

As compared with the former practice of caustic saponification of the foots followed by acidulation and distillation, without the use of an oxidizing agent, this new process has the odd characteristic of darkening the boiling soap in the kettle and of producing exceedingly dark colored fatty acids upon acidulating the soap, and yet of ending with distilled fatty acids of much lighter color and keeping qualities—fatty acids from which a soap of higher quality may be made. The function of the oxidizing agent appears to be to convert impurities in the foots to forms which settle out of the soap in the kettle and/or which are non-volatile in the fatty acid still. The manner in which the oxidizing agent functions is, however, not well understood, and the invention is not to be limited to any theory as to its mechanism.

In a number of typical comparisons it has been found that cottonseed foots of normal quality yielded fatty acids having an aged color of 20 to 25 red (5 1/4 inch column) on the Lovibond scale when the fatty acids were produced by caustic saponification, caustic washing in the kettle, acidulation, and distillation, without the use of an oxidizing agent; whereas when the same

foots were similarly processed, with the inclusion of the oxidizing step of the present invention during the kettle boiling procedure, using 0.1 per cent of potassium persulfate, the resulting acidulated and distilled fatty acids had aged colors ranging from about 9 to 12 red. By "aged color" I refer to a color measured after a sample of the fatty acids had been held for three days at 130° F. to 140° F. in contact with air.

In another typical case, fatty acids having a fresh color of 3.4 red were produced by the process of the present invention, as compared with a color of 5.2 red by prior practice in which 3 caustic washes in the kettle took the place of the oxidizing step of the invention. The aged colors in this case were 4.7 and 12.3 respectively.

Soaps made from fatty acids of the foregoing examples which were processed according to this invention were much lighter than those made by the comparable older process, and they held their color very much better when subjected to high temperatures and oxidizing conditions.

As another example of the invention, a quantity of acidulated cottonseed foots are pumped into a soap kettle containing about one half their bulk of dilute (e. g., 7 per cent) salt solution. This kettle charge is then brought up to the boiling point, and 34° caustic soda solution is slowly added while gentle boiling is continued. Soon after the addition of caustic solution has commenced, 0.1 per cent of powdered potassium persulfate (calculated on the weight of the acidulated foots charged into the kettle) is dusted over the surface of the boiling charge. After several hours of boiling and when saponification is complete, sufficient salt to grain the soap is added, the boiling is discontinued, the kettle is settled and the soap layer is transferred to acidulation and distillation treatments. These follow the same general procedure as outlined in the preceding example.

When acidulated cottonseed foots are thus treated by the present invention, it is usually found satisfactory to employ about the same percentage of persulfate as when treating raw foots. The acidulated foots are about two or three times as concentrated in total fatty acid content as the raw foots, and it therefore follows that the amount of persulfate normally used in processing acidulated foots is much less per pound of foots fatty acids than the amount used in treating raw foots. Acidulated foots appear to require less oxidizing agent per pound of fatty acids than raw foots, presumably because the acidulation and the settling after acidulation remove a certain amount of oxidizable tarry material. No fixed rule can be given for determining the optimum amount of oxidizing agent to use in treating any given amount of foots, whether raw or acidulated, because the color and general quality of foots is highly variable. A favorable amount of oxidizing agent can be approximated by subjecting several samples of the foots to be treated to small scale processing in the laboratory, following the steps to be employed in the commercial operation. As previously indicated, the use of 0.1 per cent of an alkaline persulfate has been found to be an effective amount in a great many cases; and the use of larger amounts of oxidizing agent have not been found to be proportionately more effective.

In place of potassium persulfate, a persulfate of any other cation which forms water soluble soaps may be used, e. g., sodium persulfate or ammonium persulfate. Similarly, other oxidizing agents than persulfates may be employed, pre-

vided they have cations which form water soluble soaps—such as sodium peroxide or sodium hypochlorite. Persulfates, however, are considered the most economical and satisfactory agents for the purpose.

The procedure outlined in the foregoing examples of preferred practices according to the invention may be varied in many details without departing from the scope of the invention. The kettle saponification procedure, for example, may be varied within the range of conditions known to any skilled soap maker. Washing the caustic saponified charge with water or caustic soda followed by graining out with salt may be practiced if desired, and the soap may be pitched and settled to produce neat kettle soap, although these additional steps have not been found to be particularly advantageous. The oxidizing agent may be added after the caustic saponification is complete instead of during the early stages of the saponification, although I prefer to provide the additional boiling time which is gained by adding the oxidizing agent early in the process. The steps of acidulating the soap and washing the resulting fatty acids may also be varied within the knowledge of the art, employing any convenient mineral acid, the only precaution being to provide fatty acids for distillation which are substantially free from inorganic materials.

Having thus described my invention, what I claim and desire to secure by Letters Patent is:

1. The process which comprises treating cottonseed oil refining foots with caustic soda to saponify the glyceride oil in the foots, adding from about 0.05 per cent to about 0.5 per cent (calculated on the weight of the original foots subjected to treatment with caustic) of potassium persulfate during said saponifying step while in a boiling condition, graining out the soaps, separating the grained soap from the aqueous phase, acidulating the soap with mineral acid to liberate the fatty acids of the soap, washing the fatty acids to remove inorganic impurities and distilling the fatty acids under reduced pressure.

2. The process which comprises treating acidulated cottonseed oil refining foots with caustic soda to saponify the glyceride oil in the foots, adding from about 0.05 per cent to about 0.5 per cent (calculated on the weight of the original foots subjected to treatment with caustic) of potassium persulfate during said saponifying step while in a boiling condition, graining out the soaps, separating the grained soap from the aqueous phase, acidulating the soap with sulfuric acid to liberate the fatty acids of the soap, washing the fatty acids to remove inorganic impurities, and distilling the fatty acids under reduced pressure.

3. The process which comprises saponifying with caustic soda cottonseed oil refining foots selected from the group consisting of raw foots

and acidulated foots, treating the resulting soaps with a peroxide of a cation which forms water-soluble soaps, acidulating these treated soaps thereby forming dark colored oxidation products in the resulting fatty acids, and distilling these fatty acids.

4. The process which comprises saponifying with caustic soda cottonseed oil refining foots selected from the group consisting of raw foots 10 and acidulated foots, treating the resulting soaps with from about 0.05 per cent to 0.5 percent (calculated on the weight of the foots before saponification) of a persulfate of a cation which forms water-soluble soaps, acidulating these treated soaps with mineral acid, and distilling the resulting fatty acids.

5. The process which comprises saponifying with caustic soda cottonseed oil refining foots selected from the group consisting of raw foots 20 and acidulated foots, treating the resulting soaps with a minor proportion of a persulfate of a cation which forms water-soluble soaps, acidulating these soaps with mineral acid, and distilling the resulting fatty acids.

25 6. The process of claim 5 in which the persulfate is potassium persulfate.

7. The process which comprises saponifying with caustic soda cottonseed oil refining foots selected from the group consisting of raw foots 30 and acidulated foots, treating the resulting soap with a hypochlorite of a cation which forms water-soluble soaps, acidulating these treated soaps thereby forming dark colored oxidation products in the resulting fatty acids, and distilling these fatty acids.

35 8. The process which comprises saponifying with caustic soda cottonseed oil refining foots selected from the group consisting of raw foots and acidulated foots, treating the resulting soaps

40 with an oxidizing agent selected from the group consisting of persulfates, peroxides and hypochlorites of cations which form water-soluble soaps, acidulating these treated soaps thereby forming dark colored oxidation products in the resulting fatty acids, and distilling these fatty acids.
